UNITED STATES PATENT OFFICE.

PATRICK McDERMOTT, OF MEMPHIS, TENNESSEE, ASSIGNOR TO THE MILBURN GIN AND MACHINE COMPANY, OF SAME PLACE.

KEY FOR PULLEYS.

SPECIFICATION forming part of Letters Patent No. 378,260, dated February 21, 1888.

Application filed December 24, 1886. Renewed September 7, 1887. Serial No. 249,061. (No model.)

To all whom it may concern:

Be it known that I, PATRICK McDERMOTT, of Memphis, in the county of Shelby and State of Tennessee, have invented a new and useful Improvement in Keys for Pulleys, which improvement is fully set forth in the following specification and accompanying drawings, in which—

Figure 1 is a side view of a wood split pulley equipped with one of my keys; Fig. 2, a perspective view of the cross binding pieces, partly in section; and Fig. 3, a detail view.

In the construction of what are known as "woodsplit pulleys" the parallel pieces which unite the arches or semicircles of which the pulley is composed are provided with bolts, which cause these cross arms or pieces to bind tightly upon the shaft, and are thus held in position. For ordinary pulleys, or in cases where the ordinary amount of power is transmitted, this fastening is sufficient and requires no groove and feather; but in cases where the shaft is small and the pulley large or extraordinarily heavy and a great strain is exerted it is better to provide additional means to prevent the pulley from turning on the axle; and the object of this invention is to provide a cheap and efficient means for accomplishing this purpose in such a manner that it can be readily applied by any ordinary mechanic.

The cross-bars A A are constructed in the ordinary manner, so far as relates to their adjustment to the shaft, having centrally the semicircular cross-grooves B to receive the shaft C and the bolts D D for binding the bars A to the shaft. On one side of the semicircular grooves B the cross-bars A are recessed out, as shown at E, and the key F, whose width is greater than the width of the recess, is fitted into this recessed space, made by matching the two bars together, as in Fig. 1, and suitable holes, F, are made in each cross-

bar to receive the bolts D. The key thus constructed projects into the circular space occupied by the shaft C. In order, therefore, to attach the key to the shaft, it is necessary to have a groove, G, chipped or plowed therein to receive the key. The same bolts, therefore, which tighten the bars in clamping the shaft tighten the key F and prevent the pulley from turning.

It is obvious that the key may be fitted into the gains formed between the bars A without necessitating the bolts D passing through the same, and in some cases such construction would be preferable; but in order to prevent the loss of the key, and also to add additional strength by making the key as wide as possible, I prefer for all purposes to have the bolts D pass through the key. It has sometimes heretofore been the practice, for this general purpose, to fit a collar or bushing to the cross-bars, owing to the fact that the wood adjacent to the shaft is more or less likely to be worn away by the constant pressure or strain of the bolts D when in use. By the use of the key, however, a less pressure on the part of the bolts is necessary to accomplish the same purpose, and in addition the simplicity and cheapness are apparent.

Having described my invention, what I claim as new is—

The combination of the cross-bars, each grooved and recessed as described, with the key and the bolts passing through the bars and key, said key being adapted to enter the groove in the shaft, substantially as described.

In testimony that I claim the foregoing I have hereunto set my hand, this 31st day of August, 1886, in the presence of witnesses.

PATRICK McDERMOTT.
